SCREW FEED MECHANICAL PENCIL WITH
FRICTION BRAKEHelmer R. Jochim, Downers Grove, Ill., assignor
to Rite-Rite Manufacturing Company, Downers
Grove, Ill.

Application May 31, 1945, Serial No. 596,823

11 Claims. (Cl. 120—18)

1

This invention relates to improvements in mechanical pencils or the like.

One of the objects of the invention is to provide a mechanical pencil having means to resist the propelling of the lead, i. e., unintentional lengthwise movement of the lead.

Another object of the invention is to furnish a mechanical pencil in which the parts are so constructed that they can be assembled by hand and be locked in an assembled relation without the use of rolling mechanism, crimping mechanism or the like.

With the foregoing objects outlined and with other objects in view which will appear as the description proceeds, the invention consists in the novel features hereinafter described in detail, illustrated in the accompanying drawings, and more particularly pointed out in the appended claims.

In the drawings:

Fig. 1 is an enlarged longitudinal sectional view, partly in elevation, of the front end portion of a mechanical pencil of the type improved by the present invention.

Fig. 2 is a similar view of the rear end portion and illustrating an example of the improvements.

Fig. 3 is a plan view of the channel tube of the pencil.

Fig. 4 is a similar view of the tube but taken at right angles to Fig. 3.

Fig. 5 is an end view of the same.

Fig. 6 is a side elevation partly in diametrical section of the spiral assembly.

Fig. 7 is a diametrical sectional view of the lock cup.

Fig. 8 is an elevation of the same.

Fig. 9 is a diametrical sectional view of the spring washer.

Fig. 10 is an elevation of the washer.

Fig. 11 is a side elevation of the eraser ferrule.

Fig. 12 is an end view of the same.

Fig. 13 is a view similar to Fig. 2 but illustrating a modification.

Referring first to Figs. 1 and 2, 14 designates a barrel provided with a bore 15 for the reception of the channel tube 16. As best shown in Figs. 3 to 5, inclusive, this tube may be made of rolled sheet metal and is provided with a straight longitudinal channel or guideway 17 at one side which is in alignment with a protuberance 18 projecting from the diametrically opposite side. The protuberance may cooperate with a groove (not shown) in the bore of the barrel to prevent rotation of the tube about its longitudinal axis. The

2

tube is flanged at its rear end as indicated at 19 so that it may project outwardly at one end of the barrel. Referring to Fig. 1, an externally corrugated ring 20 may be secured by a press fit as at 21 to the opposite end of the channel tube for the purpose of securing the tube against axial movement in the barrel. A guide tip 22, bored to freely receive the plunger 23, is provided with a reduced tubular end portion 24 having a press fit at 25 with the forward end portion of the channel tube. The lead which is activated by the plunger is marked 26.

Arranged within the channel tube is a spiral member 27 preferably made from metallic ribbon and forming a spiral slot 28 which cooperates with a projection 29 extending laterally from the inner end of the plunger 23 and into the slot 17 of the channel tube. It will be obvious that if the spiral member is turned about its longitudinal axis while the channel tube is stationary, the projection 29 will be moved lengthwise of the barrel 14 to propel or withdraw the lead, depending on the direction of rotation.

For turning purposes, a driving ferrule 30 is secured to the rear end of the spiral member in any suitable way. The driving ferrule may consist of a sheet metal cup provided with a re-entrant annular flange 31, embracing and secured to the spiral member, by solder or the like. The ferrule is preferably formed of resilient sheet metal and its outer rim, before the parts are assembled, is flared, as shown in Fig. 6. Therefore, when an eraser or second ferrule 32 is placed about the ferrule 30, there will be a press fit at 33 between these parts so that turning of the eraser ferrule will effect turning of the driving ferrule in the spiral member.

It will be noted from Fig. 2 that the driving ferrule slidably engages one face of the flange 19 of the channel tube while the opposite face of the flange engages a spring washer 34, preferably of dish-shape and having a plane annular surface 35 at its rim portion, engaging the bottom 36 of a lock cup 37, formed of spring metal.

From Fig. 7 it will be noted that the wall of the lock cup, before the parts are assembled, is flared, and in assembly is turned in a direction opposite to that of the rim of the driving ferrule 36, and therefore when the eraser ferrule is placed in position, there will be a press fit 38 between the lock cup and the eraser ferrule which will cause the former to turn with the eraser ferrule when it is desired to project or withdraw the lead.

It may also be seen from Fig. 2 that the eraser

ferrule is long enough to receive an eraser 40 at its rear end, and to sleeve over the rear end portion of the barrel, at its forward end, so that an ornamental bead 41 at the forward end of the ferrule may abut against an annular shoulder 42 at the exterior of the barrel. Due to this construction, it is unnecessary to secure the eraser ferrule to the barrel by rolling a portion of the ferrule into an annular groove or the like, of the barrel.

Instead of making the lock cup 37 in one piece, two parts may be used as illustrated in Fig. 13, in which case the annular rim 37a of the cup is made separate from the bottom 37b, which may be in the form of a simple washer.

From the foregoing, it is believed that the construction, operation and advantages of the invention may be readily understood, but with reference to the novel features of the improved construction, the following may be said.

The chief purpose of the spring washer 34 is to provide or set up a suitable resistance against the turning of the spiral member 27. In all mechanical pencils it is essential that the lead be held rigidly so that pressure on the lead during writing will not activate the mechanism and thereby cause undesired backward or forward movement. (It is sometimes possible to control this by the exact dimensions of each part in the pencil, but in many cases where the maximum and minimum dimensional limits are combined in interchangeable part assemblies, a looseness exists which allows the lead to be retracted by the extreme pressure on the lead when the pencil is held vertically.) The spring washer of the present invention provides a brake or pressure resisting means to prevent or eliminate unwanted movement of the lead. Furthermore, most mechanical pencils are fitted with erasers and quite often when the eraser is being used, it will have a tendency to work the mechanism either forward or backward depending upon the motion of the eraser. Thus, the spring washer sets up a resistance against this unwanted movement. Some pencils are designed so that backward and forward motion is possible but there are many types of mechanisms where this motion must be controlled or restricted, and that is one of the purposes of the spring washer 34.

There are several advantages resulting from the use of the lock cup 37, as it provides a suitable bearing surface for the spring washer in relation to the exterior of the bottom of the cup, and also provides a positive stop against the head of the barrel 14 for assembly purposes by the inside of the bottom of the cup. It also supplies a suitable surface for a press fit or locking means to properly seat the eraser ferrule, and it furnishes a bearing surface permitting the lock cup to rotate with the rotation of the eraser ferrule for smoothness in operating the mechanism.

The purpose of the combined spring washer and lock cup is to permit a spiral assembly (the track on which the clutch and plunger travel) to become affixed to the lock cup by means of a driving ferrule. If the mechanism were not suitably locked to the barrel on the rotary lock cup, the assembly would work out of the barrel, if the user attempted to propel the lead and consequently the mechanism would not function properly. Conversely, by placing the lock cup on the barrel which permits rotation, the spring washer being held in place by the channel tube, permits the driving ferrule to be forced over the lock cup and thereby locks the parts together

by very tight friction, by which the whole operating mechanism becomes a complete unit.

Heretofore, various means for locking the parts together have been proposed. Frequently, a rolling method was used wherein some of the metal of the eraser ferrule was turned into a groove in the barrel but this prevented any removal of the parts. One disadvantage of the rolling method is that any lack of uniformity or variation in the barrel surface at this point, coming in contact with some lack of uniformity of the eraser ferrule would cause an alternating variation between a tight and loose fit so that as the user propelled the lead, it would bear tightly part of the turn and then loosely during the balance of the turn, and this was quite objectionable in the common use of the pencil. The eraser ferrule in the present construction bearing upon the spring metal lock cup which in turn bears against the barrel, permits the combination fit to be manufactured to closer dimensions, resulting in far more uniform smoothness in operation.

While the foregoing taken in connection with the drawings discloses preferred embodiments of the invention, it is apparent that changes may be made in the details disclosed without departing from the spirit of the invention, as expressed in the following claims.

What I claim and desire to secure by Letters Patent is:

1. In a mechanical pencil, a barrel, a stationary channel tube positioned in the barrel and projecting from one end thereof, a spiral member rotatably mounted in the tube, a driving ferrule fixed to the spiral member and bearing against one end of the channel tube, a lock cup mounted on said barrel, a spring means arranged between the lock cup and the last-mentioned end portion of the channel tube, and a second ferrule surrounding the driving ferrule and lock cup and frictionally connected to the driving ferrule and lock cup.
2. In a mechanical pencil, a barrel, a stationary channel tube positioned in the barrel, a spiral member rotatably mounted in the tube, a driving ferrule fixed to one end portion of the spiral member and bearing against one end portion of the channel tube, a lock cup mounted on said barrel, a spring means arranged between the lock cup and the last-mentioned end portion of the channel tube, and a second ferrule surrounding a portion of the barrel, the driving ferrule and lock cup and frictionally connected to the driving ferrule and the lock cup.
3. In a mechanical pencil, a barrel, a stationary channel tube positioned in the barrel and having a flange projecting at one end thereof, a spiral member rotatably mounted in the tube, a driving ferrule fixed to the spiral member and bearing against one side of said flange, a lock cup mounted on said barrel and arranged at the opposite side of said flange, spring means arranged between the lock cup and the last-mentioned side of the flange and bearing against the cup and flange, and a second ferrule surrounding a portion of the barrel, the driving ferrule and lock cup, and frictionally connected to the driving ferrule and lock cup.
4. In a mechanical pencil, a barrel, a stationary channel tube positioned in the barrel and having a flange projecting at one end thereof, a spiral member rotatably mounted in the tube, a driving ferrule fixed to the spiral member and bearing against one side of the flange, a lock cup mounted on said barrel and arranged at the op-

posite side of the flange, spring means arranged between and bearing upon the lock cup and the flange, the driving ferrule being of cup-shape and having a rim portion projecting in a direction opposite to the rim of the lock cup, and a second ferrule surrounding the driving ferrule and lock cup and frictionally connected to the rims thereof.

5. In a mechanical pencil, a barrel, a stationary channel tube positioned in the barrel and having a flange projecting at one end thereof, a spiral member rotatably mounted in the tube, a driving ferrule fixed to the spiral member and bearing against one side of the flange, a lock cup mounted on said barrel and arranged at the opposite side of the flange, a resilient washer arranged between and bearing against the lock cup and the flange, and a second ferrule surrounding a portion of the barrel, the driving ferrule and lock cup and frictionally secured to the driving ferrule and lock cup.

6. In a mechanical pencil, a barrel, a stationary channel tube positioned in the barrel and having a flange projecting at one end thereof, a spiral member rotatably mounted in the tube, a driving ferrule fixed to the spiral member and bearing against one side of the flange, a lock cup mounted on said barrel, arranged at the opposite side of the flange and comprising a bottom washer and a ring-shaped rim, spring means arranged between and engaging the flange and the washer of the lock cup and yieldingly urging them away from one another, and a second ferrule surrounding a portion of the barrel, the driving ferrule and lock cup, and frictionally secured to the driving ferrule and the ring of the lock cup.

7. A mechanical pencil as claimed in claim 1 in which the driving ferrule includes a resilient ring normally tending to expand at one end of the rim.

8. A mechanical pencil as claimed in claim 1 in which the lock cup includes a rim of resilient material normally tending to flare toward the mouth of the cup.

9. In a mechanical pencil, a barrel, a stationary channel tube positioned in the barrel and having a flange projecting at one end thereof, a spiral

member rotatably mounted in the tube a driving ferrule bearing against one side of the flange and having its central portion fixed to the spiral member and its outer peripheral portion formed of resilient material, a lock cup mounted on the barrel, arranged at the opposite side of the flange and having a resilient rim, spring means arranged between and bearing against the lock cup and the flange for yieldingly urging them in opposite directions, and a second ferrule surrounding a portion of the barrel, the driving ferrule and lock cup, and frictionally secured to the rim of the lock cup and to the outer peripheral portion of the driving ferrule.

10. In a mechanical pencil, a barrel, a stationary channel tube positioned in the barrel and projecting from one end thereof, a spiral member rotatably mounted in the tube, a driving ferrule fixed to the spiral member and bearing against one end of the channel tube, spring means arranged between the first mentioned end of the barrel and the last mentioned end portion of the channel tube, and a second ferrule frictionally connected to and surrounding the driving ferrule.

11. In a mechanical pencil of the type having a barrel, a spiral member positioned in the barrel and projecting from one end thereof for moving the lead axially, and a rotatable member fixed on the projecting end of said spiral member for actuating the latter, resilient means arranged between said rotatable member and the last mentioned end of said barrel for resisting movement in one direction when pressure is exerted on the lead toward the spiral member and when pressure in the opposite direction is exerted on the rotatable member toward the spiral member.
